(57) **CLAIM**

The ornamental design of a lighting fixture, as shown and described.

DESCRIPTION

FIG. 1 is a top perspective view of a lighting fixture;

FIG. 2 is a front plan view thereof;

FIG. 3 is a back plan view thereof;

FIG. 4 is a left-side plan view thereof;

FIG. 5 is a right-side plan view thereof;

FIG. 6 is a top plan view thereof; and,

FIG. 7 is a bottom plan view thereof.

The broken lines shown in FIGS. 1-7 illustrate portions of the lighting fixture that form no part of the claimed design.

1 Claim, 4 Drawing Sheets
